(57) **CLAIM**

I claim the ornamental design for a controlling box, as shown and described.

DESCRIPTION

FIG. 1 is a front view of a controlling box;
FIG. 2 is a back view of a controlling box;
FIG. 3 is a top view of a controlling box;
FIG. 4 is a bottom view of a controlling box;
FIG. 5 is a left side view of a controlling box;
FIG. 6 is a right side view of a controlling box;
FIG. 7 is a front view of the front board of a controlling box shown separately for ease of illustration;
FIG. 8 is a back view of the front board of a controlling box shown separately for ease of illustration;
FIG. 9 is a top view of the front board of a controlling box;
FIG. 10 is a bottom view of the front board of a controlling box;
FIG. 11 is a left side view of the front board of a controlling box;
FIG. 12 is a right side view of the front board of a controlling box;
FIG. 13 is a back view of the backboard of a controlling box;
FIG. 14 is a front view of the back board of a controlling box;
FIG. 15 is a top view of the backboard of a controlling box;
FIG. 16 is a bottom view of the backboard of a controlling box;
FIG. 17 is a left side view of the backboard of a controlling box; and,
FIG. 18 is a right side view of the backboard of a controlling box.
